Attorney, Agent, or Firm—Richard B. O'Planick; Lisa B. Riedesel

[57] CLAIM

The ornamental design for a brush handle, as shown and described.

DESCRIPTION

FIG. 1 is a top front perspective view of a brush handle showing our new design;

FIG. 2 is a left side elevational view thereof;

FIG. 3 is a right side elevational view thereof;

FIG. 4 is a front elevational view thereof;

FIG. 5 is a bottom plan view thereof; the top plan view being a mirror image; and,

FIG. 6 is a rear elevational view thereof.

The broken lines are for illustrative purposes only and form no part of the claimed design.
